ELECTRICAL RELAY

Clarence S. Snavely, Miami Shores, Fla., assignor
to Westinghouse Air Brake Company, Wil-
merding, Pa., a corporation of Pennsylvania

Application January 5, 1952, Serial No. 265,135

18 Claims. (Cl. 200—94)

1

My invention relates to electrical relays, and particularly to electrical relays responsive to relatively high currents which prohibit the use of the usual relay magnetizing windings.

Load circuits carrying direct current of several thousand amperes require conductors of very large cross-sectional area to handle such load currents safely and without excessive heat and voltage losses. Such heavy conductors, or bus bars, are not adapted for winding the usual type of meter or relay coils. To measure the high current flow in a conductor of large cross-sectional area, meters are sometimes used which are connected in shunt with a portion or section of the conductor having a known resistance. Meters which are shunt connected to the conductors have been used to initiate various control functions in response to predetermined values of current flowing through the conductors, the meters being provided with electrical contacts which are operated at the predetermined values of the load current.

In other control applications it has been found desirable to provide a relay mechanism for a conductor or bus bar of large cross-sectional area, which relay mechanism is operated by the magnetic flux due to the current flow through the conductor, the relay mechanism being operated at a predetermined value of the load current. A bus bar relay mechanism of this type is illustrated and described in my copending application for Letters Patent of the United States, Serial No. 771,024, filed on August 28, 1947, for Electrical Relays, now Patent No. 2,584,749 issued February 5, 1952.

The relay mechanism disclosed in my copending application provides two relay structures mounted in housings of conducting material, the two housings being bolted together back-to-back to form a conducting path of suitable cross-sectional area to carry the heavy load currents of the circuit into which the relay housings are connected. In the relay mechanism disclosed in the aforesaid application, a high release to pick up ratio is obtained by features of construction described in said application, a change in the release to pick up ratio being obtained by adjustments in the magnetization of the permanent magnet provided for the relay mechanism.

It is an object of my present invention to provide a self-contained relay unit adapted to be clamped to a conductor or bus bar of large cross-sectional area carrying heavy load currents and operable by the magnetic flux due to the current flow in the conductor or bus bar.

2

Another object of my invention is to provide a relay mechanism having a high release to pick up ratio wherein mechanical means are incorporated to vary the release to pick up ratio of the relay.

These and other objects of my invention I accomplish by providing a nonmagnetic metal frame or support secured to a base of insulating material for mounting the magnetic and contact structures of the relay mechanism. The insulating base together with a backstrap cover also made of insulating material, form a clamping means whereby the relay mechanism is secured to a conductor or bus bar.

15 A one-piece molded rotor of insulating material is pivotally supported in the nonmagnetic frame, the rotor having molded therein a magnetizable armature and spring contact fingers, the spring contact fingers coacting with stationary contacts secured to the insulating base. The nonmagnetic frame of the mechanism also supports two magnetizable cores, the ends of which extend through the insulating base and through slots or openings provided in the associated conductor or bus bar. 20 The cores together with the armature and a backstrap complete the magnetic circuit for the relay, the conductor or bus bar being enclosed by the magnetic circuit.

25 The armature supporting rotor of the relay mechanism is provided with a spiral return spring, one end of which is secured to the rotor while the other end is secured to an adjustable arm. By means of an adjusting screw coacting with the adjustable arm, the tension of the spiral return spring may be increased or decreased. The tension of the spiral return spring determines the pick up value of the relay.

30 The rotor is further provided with two diametrically oppositely extending flat springs, the outer or free ends of the springs being received in slots cut into two ears or tabs of insulating material. The tabs or ears are secured to two tapped blocks threaded respectively on the oppositely threaded ends of a long screw confined by the nonmagnetic frame. By turning the long adjusting screw, the insulating tabs or ears are moved toward and away from each other. The varying of the effective length of the two flat springs in this manner varies the stiffness of the flat springs. The adjustment of the long screw controls the ratio of the release to pick up value of the relay.

35 I shall describe one form of apparatus embodying my invention and shall then point out the novel features thereof in the appended claims.

40 In the accompanying drawings, Fig. 1 is a side

elevational view of my novel relay clamped to a bus bar. Fig. 2 is a sectional view taken along the line II—II of Fig. 1. Fig. 3 is a plan view of the relay mechanism with the cover removed and portions of the frame broken away. Fig. 4 is a sectional view taken along the line IV—IV of Fig. 3. Fig. 5 is a perspective view of the relay operating mechanism with portions broken away, while Fig. 6 is a perspective view of the relay rotor assembly, portions of the rotor being broken away to show details of construction.

Similar reference characters designate similar parts throughout the several views.

Referring now in detail to the drawings, the reference character 1 designates in general a relay mechanism embodying my invention secured to a bus bar 2. The bus bar 2 is of a highly conductive, nonmagnetic material adapted to be connected in series with a load circuit (not shown) carrying several thousand amperes of direct current, by way of tangs 2a. The bus bar 2 is provided with two openings, or slots, 2b cut into the opposite edges of the bar, the slots leaving a central portion 2c of reduced cross-sectional area which conducts the entire load current through the magnetic structure of the relay mechanism 1 which I will now describe.

The relay mechanism 1 comprises a base plate 3 of insulating material formed with a suitable rectangularly shaped recess 3a in its upper surface and having molded therein two pairs of adjustable contacts; a pair of front contacts 4a and a pair of back contacts 4b. The front and back contacts 4a and 4b are connected by way of connectors 5 to the terminal posts 6a and 6b, respectively, molded in the base plate 3. Secured within the recess 3a of the base plate is a nonmagnetic frame or bracket 7 comprising a base 7a and four integral standards 7b-7e, the frame being secured to the base plate 3 by nonmagnetic screws 8 recessed in the underside of the base plate. Fixed to the upper ends of the legs 7b-7e of the frame 7 by four nonmagnetic screws 9 is a nonmagnetic plate 10 formed with a dependent circular boss 10a (Fig. 4). The boss 10a is provided with a concentric journal opening 10b which is in vertical alignment when plate 10 is secured to the frame legs, with a similar opening 7f provided in the frame base 7a.

Secured in the base 7a of the nonmagnetic frame 7 are two magnetizable cores 11 and 12 extending downwardly with some clearance through suitable openings 3b provided in the insulating base plate 3. The cores are formed with enlarged upper ends of pole pieces 11a and 12a, respectively, a portion of each of the pole pieces being milled away to form vertical pole faces 11b and 12b on the respective pole pieces. It will be noted in Fig. 3 that the vertical pole faces are parallel to each other, but angularly disposed with respect to the plane intersecting the axes of the two pole pieces.

Rotatably mounted in the nonmagnetic frame 7 for oscillation about a vertical axis is a rotor assembly 13 (Fig. 6) comprising a molded rotor 14 of insulating material having molded there-in a vertical shaft 15 and a magnetizable armature 16. In the construction of the rotor assembly, the shaft 15 is press fitted into an opening (not shown) in the center of the armature 16 before the rotor is molded. The shaft may be of a suitable magnetizable metal or it may be of a metal having the least bearing friction and wear. I thus provide a single shaft

for the rotor assembly for accurate alignment of the rotor and a low reluctance armature intersecting the shaft at right angles. The ends of the armature are formed with vertical pole faces 16a and 16b, the planes of the pole faces (Fig. 3) being angularly disposed with respect to the longitudinal axis of the armature. As will hereinafter appear, the armature pole faces 16a and 16b are so formed and the armature so mounted in the rotor assembly that the armature pole faces will be parallel with the pole faces 11b and 12b of the pole pieces when the armature is in its midstroke position.

Four spring fingers 17-20 are also molded in the rotor 14 in the same plane with the armature 16 but normal thereto, the fingers being arranged in coextensive parallel pairs extending in opposite directions from the rotor. Molded in the rotor in the central portion thereof are two diametrically oppositely extending flat springs 21 and 22, the flat springs being slightly longer than the spring contact fingers 17-20, and extending in the same directions. The flat springs 21 and 22 in addition to serving as a biasing means for the rotor 14 as will hereinafter be described, also serve as the heel connection for the spring contact fingers 17-20. The outer or free ends of the flat springs 21 and 22 are electrically connected by way of connectors 23 to the terminal posts 24a and 24b, respectively, molded in the base plate 3. As will hereinafter appear, there is very little flexing of the connectors 23 because the free ends of the springs 21 and 22 are held practically stationary. The inner ends of the flat springs 21 and 22 molded within the rotor are electrically connected to the inner ends of the spring contact fingers, the flat spring 21 being connected to the contact fingers 17 and 18 by conducting strips 25 (Fig. 6) riveted to said spring and fingers, while flat spring 22 is similarly connected to the contact fingers 19 and 20. A slot or groove 26 is provided in the upper surface of the rotor member for receiving the inner end of a coil tension spring 27, the coils of which encompass the upper end of the rotor 14.

The rotor assembly 13 is mounted within the frame 7 with the lower end of shaft 15 in the bearing provided by opening 7f in the base 7a and the upper end of the shaft in the bearing formed by the opening 10b in plate 10 when said plate is secured to the frame legs. The rotor assembly 13 is adapted to be oscillated about a vertical axis defined by the shaft 15 in a manner to be described, the armature being oscillated in the plane of the pole faces 11b and 12b of the pole pieces and the contact fingers 17-20 being oscillated in the plane of the stationary contacts 4a and 4b.

Adjustable means are provided for varying the tension of the coil spring 27 to bias the rotor assembly 13 to one extreme position in which the back contacts 4b are engaged by the spring contact fingers 17 and 19 of the rotor assembly. The tension of the coil spring 27 will determine the flux level or current value at which the back contacts 4b are disengaged and the front contacts 4a engaged by the spring contact fingers 18 and 20.

To this end an arm 28 is pivoted on the dependent boss 10a of the frame plate 10 (Figs. 4 and 5), the free end of the arm being formed with a dependent ear or abutment plate 29 which is riveted to the free end of the coil tension spring 27 of the rotor assembly. Coacting with the abutment plate 29 of the arm 28 is an adjusting

screw 30, threaded through an ear 7g of frame leg 7b, the inner end of the screw abutting the plate 29 (Figs. 3 and 5). By threading the screw 30 inwardly, the arm 28 is pivoted in a counter-clockwise direction (Fig. 3), thereby increasing the bias of the coil tension spring. To decrease the bias of the coil tension spring the adjusting screw is threaded outwardly of ear 7g.

The bias of the coil tension spring 27 tends to rotate the rotor assembly 13 in a counterclockwise direction (Fig. 3). To limit the angular displacement of the rotor assembly 13 due to the bias of the coil tension spring, nonmagnetic stop screws 31a and 31b are threaded through the frame legs 7b and 7d, the inner ends of which are adapted to abut the armature 16 in one extreme or release position in which the back contacts 4b-17 and 4b-19 are closed. It will be noted in Fig. 3 that in the release position of the armature 16 a small air gap exists between the pole faces 11b and 12b of the pole pieces and the pole faces 16a and 16b of the armature. The two sets of pole faces are practically parallel in the release position of the armature, the pole faces of the armature and pole pieces being so constructed and assembled that the two pairs of pole faces will be parallel when the armature is in its mid stroke position. To limit the rotation of the rotor assembly in a clockwise direction, nonmagnetic stop screws 32a and 32b are threaded through the legs 7c and 7e, respectively, of the frame 7; the clockwise rotation of the rotor assembly being limited to a second extreme or full-stroke position in which the front contacts 4a-18 and 4a-20 are closed and the air gaps between the armature pole faces 16a, 16b and the pole faces 11b, 12b of the pole pieces are very nearly closed. It will be appreciated that abutment of the pole faces should be avoided to prevent sticking of the armature when magnetic flux threading the armature decays.

The relay mechanism thus far described is mounted on the bus bar 2, the insulating base plate 3 engaging the top surface of the bus bar and the cores 11 and 12 extending into and through the bus bar slots 2b. The cores 11 and 12 are enclosed in sleeves 33 of insulation material (Fig. 2) to insulate the cores from the bus bar. It will be noted in Fig. 2 that the lower ends of the cores extend slightly below the bottom surface of the bus bar. A backstrap 34 of magnetizable material is provided for the lower ends of the cores 11 and 12 to complete the magnetic circuit of the relay. The backstrap 34 is enclosed by a backstrap cover 35 made of insulation material which also serves as a clamping means for securing the relay mechanism 1 to the bus bar 2.

The backstrap cover 35 is clamped to the underside of the bus bar 2 by means of four screws 36 preferably made of brass. The heads of the screws 36 are recessed in suitable openings 3c provided in the insulating base plate 3, the screws passing through openings 2d in the bus bar 2 with some clearance, and are threaded into metal inserts 37 recessed in the backstrap cover 35. A strip 38 of insulation material is interposed between the bottom face of the bus bar and the backstrap cover, the strip being suitably perforated to accommodate the cores 11 and 12 and the clamping screws 36.

The backstrap cover 35 is formed with a recess 35a to accommodate the ends of the cores 11 and 12 and the magnetizable backstrap 34. The backstrap 34 is biased upwardly against the lower

ends of the cores by a leaf spring 39 interposed between the backstrap and the bottom of the recess 35a. One or more nonmagnetic shims 40 may be inserted between the lower ends of the pole pieces 11 and 12 and the backstrap 34 to vary the reluctance of the magnetic circuit of the relay, whereby an approximate pick up value of flux may be obtained at which the relay will close its front contacts.

A cover 41 preferably of sheet steel, secured to the top plate 10 of the frame by two screws 42 and having a gasket 43 (Figs. 3 and 4) interposed between the lower edge of the cover and the base plate 3, seals the relay mechanism against the entry of foreign matter, the steel cover acting as a magnetic shield for the relay structure.

The relay mechanism thus far described will operate to open its back contacts 4b-17 and 4b-19 and close its front contacts 4a-18 and 4a-20 in response to a flow of current of predetermined value through the bus bar 2. The flow of direct current through the bus bar creates a magnetic field encircling the bus bar in closed loops. The magnetizable cores 11 and 12 being in the magnetic field set up by the current flowing through the central portion 2c of the bus bar, together with the backstrap 34 and the armature 16, offer a relatively low reluctance path for the encircling magnetic lines of force of the magnetic field. The armature 16, being biased in a counterclockwise direction by the coil spring 27, will be attracted to the pole faces 11b and 12b against the bias of the spring 27 when the flux in the magnetic circuit exerts a force greater than the biasing force of the spring 27.

The operation of the armature 16 in response to the flux threading the magnetic circuit of the relay may be varied by varying the reluctance of the magnetic circuit by including therein the nonmagnetic shims 40, or by varying the tension of the spring 27 biasing the rotor assembly. By varying the reluctance of the magnetic circuit an approximate range of current values at which the relay will close its front contacts is established and by varying the tension of the coil spring 27 the pick up current value of the relay may be accurately determined.

The coil spring 27 biasing the rotor assembly 13 is a long spring, and the biasing force exerted thereby may be considered as remaining constant in any position of the armature from its release position to its full-stroke position. When the magnetic force exerted on the armature is greater than the biasing force of the coil spring, the armature will move toward its full-stroke position, thereby decreasing the widths of the air gaps between the pole faces of the armature and the pole pieces. The torque exerted on the armature by the magnetomotive force thus increases while the biasing torque of the coil spring remains constant, so that the armature moves to its full-stroke position with a snap action. Since the air gaps between the armature and the pole pieces are narrower when the armature is in its full-stroke position than when in its release position, a lesser magnetomotive force is required to hold the armature in its full-stroke position than to move the armature from its release position against the bias of the coil spring. The current or pick up value at which the relay will close its front contacts is thus greater than the current or release value at which the relay will open its front contacts.

Considering for the moment, a short spring

biasing the rotor assembly 13 in place of the long spring 27, and a torque exerted on the armature by the magnetomotive force sufficient to overcome the bias of the short spring, the movement of the armature from its release position toward its full-stroke position will increase the biasing torque of the short spring. The decreasing widths of the air gaps between the armature and the pole pieces will decrease the reluctance of the magnetic circuit so that an increasing torque is exerted on the armature by the magnetomotive force. The increasing torques exerted on the armature tend to balance each other with the result that the armature creeps to its full-stroke position. When the armature is in its full-stroke position, the magnetomotive force acting upon the armature will be at its maximum, but the biasing force of the short spring will also be at its maximum. Thus any small change in the value of the current creating the magnetomotive force will permit the return of the armature to its release position. With a short spring biasing the rotor assembly, the current, or pick up value at which the relay will close its front contacts is thus approximately equal to the current, or release value at which the relay will open its front contacts.

In providing an electrical relay having a high ratio of release to pick up value I combine the biasing influences of two springs, a long spring such as the coil spring 27 described and a short spring such as the flat springs 21 and 22 which I will now describe in detail; the spring arrangement being such that I retain the snap action of a rotor assembly influenced by a long spring and the high ratio of release to pick up value of a relay having a rotor assembly influenced by a short spring, the spring arrangement also providing means whereby the ratio of the release to pick up value may be accurately controlled.

To this end, the free ends of the flat springs 21 and 22 are confined in slots 44a cut in tabs 44 of insulation material. The tabs 44 are secured to threaded blocks 45 which are threaded on the oppositely threaded ends of an adjustment screw 46, the ends of the flat springs being held and tending to bias the armature toward its mid-stroke position. The adjustment screw 46 is rotatably mounted in the frame legs 1d and 1e, the screw being confined in the frame by a sleeve or collar 47 pinned to the screw between the supporting frame legs (Figs. 3 and 4). By turning the adjustment screw one way or the other, the blocks 45 carrying the confining tabs 44 may be moved toward or away from each other to vary the effective lengths of the two flat springs 21 and 22. By varying the effective lengths of the springs, the stiffness of the two springs is varied without producing any reaction force which may cause friction and wear at the pivot points.

The general effect of stiffening the flat springs 21 and 22 is to increase the bias of the rotor assembly toward its mid-stroke position. This biasing effect of the two flat springs tends to reduce the force exerted by the spiral spring in holding the rotor assembly in its released position with the armature 16 abutting the stops 31a, 31b. The restoring force of the spiral spring 27 in returning the rotor assembly from its full-stroke position is increased by the centering effect of the two flat springs 21 and 22. As a result of this modulating action on the spiral spring torque by the centering torque of the flat springs, the pick up value of the relay will be reduced since

the centering torque of the flat springs partially offsets the biasing torque of the coil spring. The release value of the relay will be increased since the centering torque of the flat springs now aids the restoring force of the coil spring. The adjustment of the effective lengths of the flat springs 21 and 22 by the adjustment screw thus controls the ratio of release to pick up values of the relay.

10 The relay mechanism herein described may be advantageously used with a bus bar permanently connected in service, any replacement or servicing of the relay being accomplished by handling of the small self-contained relay unit. The calibration of the relay mechanism is also more easily effected, the relay mechanism being removed from the bus bar and reassembled to test coils having a fixed number of turns, so that the relay can be calibrated from a low current source. The adjustments of the coil spring and of the flat springs of the rotor assembly are also advantageous in that such adjustments of the tension or stiffness of the springs may be readily and accurately made, the adjustment of the effective lengths of the two flat springs to vary the ratio of release to pick up values of the relay being simpler than methods provided in the prior art. Such adjustments may readily be made without disassembly of the relay unit, and may even be made through a cover or shield suitably provided with openings for insertion of a screw driver.

30 Although I have herein shown and described only one form of an electrical relay embodying my invention, it is understood that various changes and modifications may be made therein within the scope of the appended claims without departing from the spirit and scope of my invention.

40 Having thus described my invention, what I claim is:

1. In combination, a member mounted for movement between two extreme positions, a first spring biasing said member toward a position intermediate the two extreme positions, the bias of said first spring increasing as said member is moved from the intermediate position toward either of the two extreme positions, a longer second spring biasing said member to one extreme position against the bias of said first spring, the bias of said second spring remaining substantially uniform throughout the range of movement of said member, and means for applying a force of predetermined magnitude to move said member from the one extreme position to the other extreme position, said first and second springs coacting to move said member from the other extreme position when the force applied to said member is less than the predetermined magnitude.

2. In combination in accordance with claim 1 in which means are included to vary the bias of said second spring to vary the magnitude of the force required to move said member from the one extreme position to the other extreme position.

3. The combination in accordance with claim 2 in which means are included to vary the bias of said first spring to vary the ratio of the magnitude of the force applied to said member in its other extreme position which permits movement of said member from the other extreme position by said springs, to the magnitude of the force

required to move said member to the other extreme position.

4. The combination in accordance with claim 3 in which the first spring is a flat spring and the longer second spring is a coil spring, and in which the means to vary the bias of said first spring includes a confining member for the spring to vary the effective length thereof.

5. In an electrical relay, the combination comprising, a magnetizable core structure including a member movable between two extreme positions, and two mechanical force exerting means coacting with said movable member, each exerting a force of different magnitude on said member; the first of said means tending to move said member to a position intermediate its two extreme positions and the second of said means moving said member to one of its extreme positions, said member being moved from the one extreme position to the other extreme position in response to magnetic flux of a predetermined level supplied to said core structure, the force exerted by the first of said means on said member increasing as said member is moved from the intermediate position toward either of its two extreme positions; the force exerted by the second of said means on said member being substantially uniform throughout the range of movement of said member; both of said means coacting to move said member from its other extreme position toward its one extreme position when the magnetic flux level supplied to said core structure falls below the magnetic flux level at which said member was moved from its one extreme position to its other extreme position.

6. In an electrical relay, the combination comprising, a magnetizable core structure including a member movable between two extreme positions, and two springs coacting with said movable member, each spring exerting a force of different magnitude on said member; one of said springs tending to bias said member to a position intermediate the two extreme positions, the other of said springs biasing said member to one extreme position in opposition to the bias of the one spring; said member being moved from the one extreme position to the other extreme position in response to magnetic flux of a predetermined level supplied to the core structure; the force exerted by the one spring on said member increasing as said member is moved from the intermediate position toward either of its extreme positions; the force exerted by the other of said springs on said member being substantially uniform throughout the range of movement of the member; both of said springs coacting to move said member from the other extreme position toward the one extreme position when the level of the magnetic flux supplied to the core structure falls below the magnetic flux level at which said member was moved from the one extreme position to the other extreme position.

7. In an electrical relay, the combination comprising, a magnetizable core structure including a member movable between two extreme positions, two springs coacting with said movable member, each spring exerting a force of different magnitude on said member; one of said springs tending to bias said member to a position intermediate the two extreme positions, the other of said springs biasing said member to one extreme position in opposition to the bias of the one spring, said member being moved from the one extreme position to the other extreme position in response to magnetic flux of a predetermined

level supplied to the core structure; the force exerted by the one spring on said member increasing as said member is moved from the intermediate position toward either of its extreme positions; the force exerted by the other of said springs on said member being substantially uniform throughout the range of movement of the member, both of said springs coacting to move said member from the other extreme position toward the one extreme position when the magnetic flux level supplied to the core structure falls below the magnetic flux level at which said member was moved from the one extreme position to the other extreme position, and means for varying the bias of each of said springs to vary the magnetic flux level at which said member is moved to its other extreme position and the ratio of the magnetic flux level at which said member is moved from its other extreme position to the magnetic flux level at which the member is moved to its other extreme position.

8. In an electrical relay, the combination comprising, a magnetizable core structure including a member movable between two extreme positions, a flat spring tending to bias said member to a position intermediate the two extreme positions, and a coil spring biasing said member to one extreme position, said member being moved from the one extreme position to the other extreme position in response to magnetic flux of a predetermined level supplied to the core structure; the force exerted by the coil spring on said member being substantially uniform throughout the range of movement of the member, the force exerted by the flat spring on said member increasing as said member is moved from the intermediate position toward either of its extreme positions; both of said springs coacting to move said member from the other extreme position toward the one extreme position when the magnetic flux level of the core structure falls below the magnetic flux level at which the member was moved from the one extreme position to the other extreme position.

9. In an electrical relay, the combination comprising, a magnetizable core structure including a member movable between two extreme positions, a flat spring tending to bias said member to a position intermediate the two extreme positions, a coil spring biasing said member to one extreme position, said member being moved from the one extreme position to the other extreme position in response to magnetic flux of a predetermined level supplied to the core structure; the force exerted by the coil spring on said member being substantially uniform throughout the range of movement of the member, the force exerted by the flat spring on said member increasing as said member is moved from the intermediate position toward either of its extreme positions; both of said springs coacting to move said member from the other extreme position toward the one extreme position when the magnetic flux level of the core structure falls below the magnetic flux level at which the member was moved from the one extreme position to the other extreme position, and means for varying the bias of each of said springs to vary the magnetic flux level at which said member is moved from its one extreme position to its other extreme position and to vary the ratio of the magnetic flux level at which said member is moved from its other extreme position to the magnetic flux level at which the member is moved to its other extreme position.

10. An electrical relay comprising a nonmagnetic frame member, magnetizable core members

secured in said frame, a rotor pivotally mounted in said frame including a magnetizable armature for oscillation between two extreme positions, a pair of oppositely extending flat springs secured in said rotor, means for confining the free ends of said flat springs to bias said rotor to a position intermediate the two extreme positions, and a coil spring secured at one end in said rotor and at the other end with said frame to bias said rotor to one extreme position against the bias of said flat springs, said rotor being moved to the other extreme position by said armature in response to magnetic flux of a predetermined level supplied to said core members, said flat springs and said coil spring coacting to move said rotor from the other extreme position when the magnetic flux level in said core members falls below the magnetic flux level at which said armature was moved to the other extreme position.

11. An electrical relay comprising a nonmagnetic frame member, magnetizable core members secured in said frame, a rotor pivotally mounted in said frame including a magnetizable armature for oscillation between two extreme positions, a pair of oppositely extending flat springs secured in said rotor, an adjustment screw confined in said frame member and having oppositely threaded ends, two confining members threaded on the ends of said screw and confining the ends of said flat springs, the turning of said adjustment screw moving said confining members toward and away from each other to vary the effective lengths of said flat springs, said flat springs biasing said rotor to a position intermediate the two extreme positions, and a coil spring secured at one end in said rotor and at the other end to said frame to bias said rotor to one extreme position against the bias of said flat springs, said rotor being moved to the other extreme position by said armature in response to magnetic flux of a predetermined level supplied to said core members, said flat springs and said coil spring coacting to move said rotor from the other extreme position when the magnetic flux level in said core members falls below the magnetic flux level at which said armature was moved to the other extreme position.

12. An electrical relay comprising a nonmagnetic frame member, magnetizable core members secured in said frame, a rotor pivotally mounted in said frame including a magnetizable armature for oscillation between two extreme positions, a pair of oppositely extending flat springs secured in said rotor, an adjustment screw confined in said frame member and having oppositely threaded ends, two confining members threaded on the ends of said screw and confining the ends of said flat springs, the turning of said adjustment screw moving said confining members toward and away from each other to vary the effective lengths of said flat springs, said flat springs biasing said rotor to a position intermediate the two extreme positions, a coil spring secured at one end to said rotor; an arm pivoted to said frame member, the end of said arm being secured to the other end of said coil spring, a second adjustment screw threaded in said frame for abutting the end of said arm, the turning of said second adjustment screw varying the tension of said coil spring, said coil spring biasing said rotor to one extreme position against the bias of said flat springs, said rotor being oscillated to the other extreme position by said armature in response to magnetic flux of a predetermined level supplied to said core members, the tension of said coil spring determining the magnetic flux

5 level at which said armature is moved to the other extreme position; said flat springs and said coil spring coacting to move said rotor from the other extreme position when the magnetic flux level falls below the magnetic flux level at which said armature was moved to the other extreme position; the variation of the effective lengths of the flat springs varying the ratio of the magnetic flux level at which the rotor is moved from the other extreme position to the magnetic flux level at which the rotor is moved to the other extreme position.

13. An electrical relay operable in response to current flowing in a bus bar comprising a non-magnetic frame member, magnetizable core members secured in said frame and adapted to be positioned in the magnetic field established by the current flowing in said bus bar, a rotor of insulation material pivotally mounted in said frame including a magnetizable armature for oscillation between two extreme positions, a pair of oppositely extending flat springs secured in said rotor, means for confining the free ends of said flat springs, said flat springs biasing said rotor to a position intermediate the two extreme positions, a coil spring secured at one end to said rotor and at the other end with said frame member to bias said rotor to one extreme position against the bias of said flat springs; said rotor being moved to the other extreme position by said armature in response to magnetic flux threading said armature and core members of a predetermined magnitude determined by the value of the current traversing the bus bar, said flat springs and said coil spring coacting to move said rotor from the other extreme position when the value of the current through the bus bar falls below the value of the bus bar current at which the rotor is moved to the other extreme position, means for varying the bias of said coil spring to vary the value of the current at which said rotor is moved to the other extreme position, and means for moving said confining means on the ends of said flat springs toward and away from each other to vary the effective lengths of the flat springs to vary the ratio of the value of the current at which the rotor is moved from the other extreme position to the value of the current at which the rotor is moved to the other extreme position.

14. In combination, a member pivoted for oscillation between two extreme positions; two oppositely extending flat springs, each secured at one end to said member; a confined adjustment screw coextensive with the flat springs and oppositely threaded at each end, and a confining member threaded on each end of said screw and confining the free end of a flat spring, the turning of said screw moving said confining members toward and away from each other to vary the effective lengths of said flat springs, said flat springs biasing said member to a position intermediate the two extreme positions.

15. In combination, a member pivoted for oscillation between two extreme positions; two oppositely extending flat springs, each secured at one end to said member; a confined adjustment screw coextensive with the flat springs and oppositely threaded at each end, a confining member threaded on each end of said screw and confining the free end of a flat spring, the turning of said screw moving said confining members toward and away from each other to vary the effective lengths of said flat springs, said flat springs biasing said member to a position intermediate the two extreme positions, a coil spring secured

at one end to said member, an arm pivoted at one end and having its free end secured to the free end of said coil spring, a second adjustment screw abutting the free end of said arm to vary the tension of said coil spring, said coil spring biasing said member to one extreme position, and means for applying a force to said member to move said member from the one extreme position to the other extreme position, said coil spring and said flat springs moving said member from the other extreme position when the magnitude of the force required to move said member to its other extreme position is decreased.

16. In an electrical relay operable in response to current flowing in a bus bar having two spaced openings therein, the combination comprising a base plate of insulation material, a nonmagnetic frame member secured to said base plate, two magnetizable core members secured in said frame member and passing through said base plate, a rotor assembly pivotally mounted in said frame member including a magnetizable armature for oscillation between two extreme positions; said core members being adapted to extend through the bus bar openings when said base plate abuts the bus bar, a magnetizable backstrap for the ends of said core members extending through the bus bar openings, a cover of insulation material accommodating said backstrap, means for clamping said cover and said base plate to said bus bar, and resilient means interposed between said cover and said backstrap to bias said backstrap against the extending ends of said core members.

17. An electrical relay operable in response to current flowing in a bus bar having two slots cut into the opposite edges thereof, comprising a base plate of insulation material, a nonmagnetic frame secured to said base plate, two magnetizable core members secured in said frame member and extending through said base plate, a rotor of insulation material pivotally mounted in said frame including a magnetizable armature for oscillation between two extreme positions, a pair of oppositely extending flat springs secured in said rotor, means for confining the free ends of said flat springs, said flat springs biasing said rotor to a position intermediate the two extreme positions, a coil spring secured at one end to said rotor and at the other end with said frame member to bias said rotor to one extreme position against the bias of said flat springs; said core members being adapted to extend through the bus bar slots when the base plate abuts the bus bar, a magnetizable backstrap for the ends of said core members extending through the bus bar slots, a cover of insulation material accommodating said backstrap, means for clamping said base plate and said cover to said bus bar, and resilient means interposed between said cover and said bus bar to bias said backstrap against the extending ends of said core members; said rotor being moved to the other extreme position by said armature in response to magnetic flux threading said armature, backstrap and core members of a predetermined magnitude determined by the value of the current traversing the bus bar, said flat springs and said coil spring coacting to move said rotor from the other extreme position when the value of the current through the bus bar falls below the value of the bus bar current at which the rotor was moved to the other extreme position.

the value of the current through the bus bar falls below the value of the bus bar current at which the rotor was moved to the other extreme position.

5 18. An electrical relay operable in response to current flowing in a bus bar having two slots cut into the opposite edges thereof, comprising a base plate of insulation material, a nonmagnetic frame secured to said base plate, two magnetizable core members secured in said frame member and extending through said base plate, a rotor of insulation material pivotally mounted in said frame including a magnetizable armature for oscillation between two extreme positions, a pair of oppositely extending flat springs secured in said rotor, means for confining the free ends of said flat springs, said flat springs biasing said rotor to a position intermediate the two extreme positions, a coil spring secured at one end to said rotor and at the other end with said frame member to bias said rotor to one extreme position against the bias of said flat springs; said core members being adapted to extend through the bus bar slots when the base plate abuts the bus bar, a magnetizable backstrap for the ends of said core members extending through the bus bar slots, a cover of insulation material accommodating said backstrap, means for clamping said base plate and said cover to said bus bar, resilient means interposed between said cover and said bus bar to bias said backstrap against the extending ends of said core members; said rotor being moved to the other extreme position by said armature in response to magnetic flux threading said armature, backstrap and core members of a predetermined magnitude determined by the value of the current traversing the bus bar, said flat springs and said coil spring coacting to move said rotor from the other extreme position when the value of the current through the bus bar falls below the value of the bus bar current at which the rotor is moved to the other extreme position, means for varying the bias of said coil spring to vary the value of the current at which said rotor is moved to the other extreme position, and means for moving said confining means on the ends of said flat springs toward and away from each other to vary the effective lengths of the flat springs to vary the ratio of the value of the current at which the rotor is moved from the other extreme position to the value of the current at which the rotor is moved to the other extreme position.
